UNITED STATES PATENT OFFICE.

JOHN B. OWENS, OF TAMPA, FLORIDA.

TUNNEL KILN.

Application filed March 3, 1927. Serial No. 172,441.

This invention relates to tunnel kilns of that general class set forth in my Patent No. 1,356,397, October 19, 1920, and it is an improvement on the kiln set forth in 5 said patent in respect to the use of a plurality of combustion chambers arranged in a series for the purpose of subjecting the goods or ware to a longer "soaking heat".

As fully explained in Patent No. 1,356,397 10 and in certain of my other patents the method of firing the combustion chambers of the burning zone in the general direction of their length and deflecting and radiating from said combustion chambers into the tunnel the heat and products of combustion, has 15 very great advantages. When this principle of firing is utilized in connection with a plurality of combustion chambers arranged in succession, as proposed in my Patent No. 20 1,356,397, even greater advantages are obtained. The object of the present invention is to obtain a more even distribution of the "soaking heat" effect at a high temperature throughout the entire length of the combustion 25 chamber for the purpose of burning the ware even more thoroughly and regularly than is possible with a kiln of the type set forth in my Patent No. 1,356,397.

This is accomplished by the provision of 30 a plurality of combustion chambers which, while independently fired in the general direction of their lengths and arranged in a series, nevertheless are, in effect, compartments or sub-divisions of a single combustion chamber, the compartments or combustion chambers being relatively arranged so that the radiated and deflected heat and products of combustion issuing into the tunnel from the chamber farthest from the preheating zone blend with, and supplement, radiated heat and deflected products of combustion from the next compartment or chamber, and such heat and products of combustion join with or blend into the heat and products of 40 combustion from the next chamber. The result is that there is an even distribution of the "soaking heat" throughout the length of the burning zone and the temperature is maintained at a high degree. Consequently, the 45 ware, which has been preheated as it ap-

proaches the burning zone, is subject to a relatively long "soaking heat" while moving faster than has heretofore been possible if adequate burning is to be obtained, the result being that the quality and rate of production of the burned ware is greatly increased. 55

The respective combustion chambers are provided with inclined baffling or deflecting end walls which direct the heat not only into 60 the tunnel and against the ware, in conjunction with the deflecting action of the crown or arch of the combustion chambers, but these inclined walls facilitate the blending of the heat and products of combustion 65 from one chamber with those of the next chamber.

Preferably, in accordance with modern practice, oil or gas burners are used for producing the heat in the respective combustion chambers but coal, coke, wood, or any other fuel may be used in lieu of oil or gas. 70

The chambers are duplicated on opposite sides of the tunnel, in accordance with present day practice. 75

I have illustrated but three subdivisions of the combustion chamber but I do not limit myself to any number as two or more may be employed. 80

One of the features of my present invention is that the side walls of the combustion chamber at points intermediate the compartments or chambers thereof, are farther apart, considered transversely of the kiln, than the 85 interior width of the tunnel. I do not, however, limit the invention to this particular feature. This provides adequate space for the heat and products of combustion issuing from one chamber to pass along the sides 90 of the ware in the burning zone and join or blend with the heat and products of combustion from the next chamber.

Another feature of the invention is that the deflecting end walls do not rise all the 95 way up to the arch or crown of the kiln in the burning zone but there is a space above them which runs the entire length of the multiple combustion chamber which further assists in enabling the heat and prod- 100

ucts of combustion from one chamber to join and blend with the heat and products of combustion of the next chamber.

I do not limit myself to any particular length or extent of this side wall, as it may project into the kiln. Neither do I limit to any particular size of the space above this wall as it may, in some instances, be desirable to extend the wall upwardly until it comes into contact with the crown of the chamber.

In the accompanying drawings:

Figure 1, is a longitudinal section through a kiln having the present improvements;

Fig. 2, is a vertical section on the line 2—2, Fig. 1;

Fig. 3, is a similar view on the line 3—3, Fig. 1;

Fig. 4, is a detail elevation looking toward the exterior of the combustion chambers; and

Fig. 5, is a detail horizontal section on the line 5—5, Fig. 2.

The tunnel of the kiln appears at 1, the stack or other draft means at 2, and the rails on which the cars travel are shown at 3.

The cars carrying the goods or ware enter at the right-hand end of the kiln, Fig. 1, as indicated at 4 and emerge from the left-hand end thereof as indicated at 5. The preheating zone of the kiln is shown at 6 and the cooling zone appears at 7.

The burning zone is indicated at 8.

As explained in my Patent No. 1,356,397, great advantages are obtained by providing a "multiple" firing or burning zone, that is, one which is much longer than is possible by the use of a single combustion chamber.

I have indicated the burning or firing zone as of substantially three times the length of the usual "single" zone but it will be understood that it might be but twice the length or, on the other hand, four times the length of a single zone.

In consequence of providing a multiple firing zone, the goods or ware become subjected to a long "soaking heat" which enables the cars to be speeded up as compared to their necessary slowness of travel in a single firing zone kiln.

The multiple combustion or firing chambers according to the present invention are shown at 9, 10, 11. They are of substantially the same length although they may vary in length, if preferred. Preferably, in interior conformation these chambers are alike. All of them are fired in the general direction of their length, that is, in a general longitudinal relationship to the length of the tunnel 1 and, may, if desired, be substantially parallel to the length of said tunnel but need not necessarily be so. It is to be understood, however, as has been pointed out in my earlier patents, that by longi-

tudinal firing, I mean in the general direction of the length of the combustion chamber and not, necessarily in exact parallelism to the tunnel or to the direction of travel of the ware.

The combustion chambers are provided with firing openings 12 through which liquid or gaseous fuel is delivered from any suitable nozzles or burners 13 having any ordinary or preferred valves or controlling means. The direction of introduction of the liquid or gaseous fuel is that of the length of the combustion chamber and in a direction opposite to the travel of the ware on the usual kiln cars. I may use coal, coke, wood, or any other fuel, in lieu of oil or gas, for the burning of the products passing through the kiln, admitting the gases from the same into the kiln through the openings 12. The arrows in Figs. 1 and 5 indicate the direction of travel of the kiln cars, one of said cars appearing at 14, Figs. 2 and 3 and travelling on the rails 3. The ware or goods to be burned is shown in diagrammatic form only at 15.

At opposite ends of the combustion chambers 9, 10, 11, there are provided the baffling or deflecting walls 16 which are arranged at an angle to the length of the kiln. The deflecting walls or baffles 16 do not have to be disposed at any exactly predetermined angle nor need they be of any exact length, as they may extend as far as the main walls of the tunnel on either side of the combustion chamber in some installations. It is only necessary that the angularity of the walls 16 be such as to adequately deflect the heat and products of combustion into the burning zone 8 of the tunnel 1 in a direction which will, under the action of the draft through the stack 2, deliver the heat and products of combustion into the burning zone in such manner that they will readily pass into the tunnel. The angle of these walls or baffles 16 should be sufficiently great in reference to the longitudinal axis of the tunnel that highly developed combustion will occur in each chamber 9, 10, 11, due to retardation of the flow from the chambers into the tunnel.

In order that the flow of the heat and products of combustion from chamber 9 may augment and join the flow from chamber 10, and the flow from chambers 9 and 10 may join the flow from chamber 11, I have found that it is very advantageous to provide spaces 17 to permit the action just described but these spaces may be omitted and the walls extended out to the lines of the side walls of the tunnel in some installations. When the spaces 17 are provided the effect is that there is practically an even distribution of the heat from chambers 9, 10, and 11 to the ware 15 on the cars 14 during the period that the ware remains in the burning zone 8,

whereas if the spaces 17 were not provided, the practically even or nearly even distribution of the "soaking heat" effect would not be obtained in as highly satisfactory a manner.

Referring to Fig. 2, it will be seen that the deflecting or baffling walls 16 do not extend all the way up to the arch 18 which forms the top of the burning zone and joins the series of chambers 8, 10, 11 on one side of the kiln with those on the other side thereof. The purpose is to provide spaces 19 for the passage of the heat and products of combustion over the tops of the walls joining the combustion chambers. In this manner the entire height of the stack of ware 15 is subject to heat radiated laterally and also downwardly in relation to the stack 15 and there is no choking of the flow en route to the draft stack 2 nor too great concentration on the middle part of the ware 15. I may, in some installations, find it expedient to run the walls 16 clear up to the arch 18, or nearly so, instead of providing the spaces 19.

To permit the convenient regulation of the burners or nozzles 13, the outside of the combustion chambers are provided with entrant parts or pockets 20 into which an operative may reach or walk to manipulate the nozzles or burners. Suitable peep-holes 21 are provided in the walls of the combustion chambers to enable operatives to inspect the firing conditions prevailing in the chambers 9, 10, and 11.

What I claim is:

1. A tunnel kiln having a multiple firing or burning zone comprising a plurality of combustion chambers arranged in succession, each provided with an angularly arranged deflecting or baffling wall, said chambers being in communication.

2. A tunnel kiln having a multiple firing or burning zone comprising a plurality of combustion chambers arranged in succession, each provided with an angularly arranged deflecting or baffling wall, and means for firing each of said combustion chambers independently of the other chambers in the general direction of the length thereof to direct the flame and products of combustion against the angularly arranged deflecting or baffling wall, in each instance, said chambers being in communication.

3. A tunnel kiln having a multiple firing or burning zone comprising a plurality of combustion chambers each provided with an upright angularly arranged deflecting or baffling wall, and an arch for the said chambers and the tunnel, the deflecting or baffling walls terminating short of said arch, thereby providing spaces affording communication between the combustion chambers.

4. A tunnel kiln having a multiple firing or burning zone comprising a plurality of combustion chambers each provided with an

upright angularly arranged deflecting or baffling wall, an arch for the said chambers and the tunnel, the deflecting or baffling walls terminating short of said arch, thereby providing spaces affording communication 70 between the combustion chambers, and means for firing each of the combustion chambers in the general direction of its length to direct the flame and products of combustion against the deflecting or baffling 75 wall and to cause the heat and products to not only pass into the tunnel but to pass over the deflecting walls into the next chamber.

5. A tunnel kiln having a multiple firing 80 or burning zone comprising a plurality of combustion chambers arranged in succession, each provided with an angularly arranged deflecting or baffling wall, the side walls of the tunnel being provided with channels 85 or spaces which permit the heat and products of combustion from one chamber to join or blend with the heat and products of combustion from the next chamber alongside the ware in the burning zone. 90

6. A tunnel kiln having a multiple firing or burning zone comprising a plurality of combustion chambers arranged in succession, each provided with an angularly arranged deflecting or baffling wall the side walls 95 of the tunnel being provided with channels or spaces which permit the heat and products of combustion from one chamber to join or blend with the heat and products of combustion from the next chamber alongside the ware in the burning zone, and means 100 for firing each of said combustion chambers in the general direction of its length to direct the flame and products of combustion against the angularly arranged deflecting 105 or baffling walls.

7. A tunnel kiln having a multiple firing or burning zone comprising a plurality of combustion chambers each provided with an angularly arranged deflecting wall, said combustion chambers being connected by channels or spaces which permit the heat and products of combustion from one chamber 110 to join or blend with the heat and products of combustion from the next chamber 115 alongside the ware in the burning zone, an arch for the top of the said chambers and the tunnel, said arch rising above the sides of the combustion chambers and located above, and free of, the baffling or deflecting falls, thereby providing spaces connecting the combustion chambers above said deflecting or baffling walls.

8. A tunnel kiln having a multiple firing or burning zone comprising a plurality of combustion chambers each provided with an angularly arranged deflecting wall, said combustion chambers being connected by channels or spaces which permit the heat and products of combustion from one cham- 125 130

ber to join or blend with the heat and products of combustion from the next chamber alongside the ware in the burning zone, an arch for the top of the said chambers and the tunnel, said arch rising above the sides of the combustion chambers and located above, and free of, the baffling or deflecting walls, thereby providing spaces connecting

the combustion chambers above said deflecting or baffling walls, and means for 10 firing each of said combustion chambers in the direction of its length to direct the flame and products of combustion against the angularly arranged or deflecting walls.

In testimony whereof I affix my signature.
JOHN B. OWENS.
